CHARLES F. LINDEBURG, OF NEWARK, NEW JERSEY.

GLASS-POLISHING MACHINE.

1,251,251.

Specification of Letters Patent. Patented Dec. 25, 1917.

Application filed August 12, 1916. Serial No. 114,495.

To all whom it may concern:

Be it known that I, CHARLES F. LINDEBURG, a citizen of the United States, and a resident of Newark, in the county of Essex and State of New Jersey, have invented certain new and useful Improvements in Glass-Polishing Machines, of which the following is a specification.

This invention relates to that class of glass

10 polishing machines for use in polishing pieces of glass for clock fronts, mirrors, and so forth the surface of which it is desired to polish. The invention is, however, not to be understood as restricted to small pieces 15 of glass, as it is applicable to both large and small, and further is applicable to plane, concave or convex, and other shaped pieces of glass.

The objects of the invention are to provide 20 a glass polishing machine which will obtain the desired results in minimum time; to polish the glass on both sides at the same time; to avoid holding the glass by a clamp while polishing it; to move the buffers toward 25 the glass from opposite sides; to stop rotation of the buffers when they are withdrawn from the glass; to obtain a pressure upon the buffers with least amount of friction on the spindles; to hold the buffers positively 30 pressed toward each other or positively drawn apart; to protect the operator from glass coming out; to secure simplicity of construction and operation and to obtain other advantages and results as may be 35 brought out in the following description.

Referring to the accompanying drawings, in which like numerals of reference indicate the same parts throughout the several views,

Figure 1 is an elevation of a glass polishing machine embodying my invention, looking at the same from the front or side at which the operator stands;

Fig. 2 is a transverse section on line 2—2 of Fig. 1;

Fig. 3 is a perspective view of a certain cradle, and

Fig. 4 is a perspective view of a shield.

In the specific embodiment of the invention, reference numeral 1 indicates a base or body portion having feet 2, 2 at its bottom for support and providing a web portion from the upper edge of which arms 3, 3 and 4, 4 project in substantially the same plane. These arms are spaced apart along the top of said web, one pair 3, 3 being at opposite ends of the web, and the other

pair 4, 4 being included between the outer pair. Bearings 5, 5 and 6, 6 are provided at the tops of each of these arms in substantial alinement and carried in the bearings are spindles 7, 8, one spindle being carried by the two bearings 5, 6 at one end of the base, and the other spindle being carried by the two bearings at the other end of the base.

65 Mounted at the inner or adjacent ends of the spindles are buffers 9, 10 between which the glass is inserted for polishing. In the present illustration, the buffers are shown as similar, with plane facing surfaces, and 70 it may be noted that these buffers are to be used for flat pieces of glass, but where it is desired to polish curved glass such as used for watch crystals, and so forth, one of the buffers is made concave and the other 75 convex, similarly for glass of other shapes, the buffers are made to correspond to the shape of the glass. The spindles are not only rotatably mounted in the bearings 5, 6, but are slidable therein, so that the buffers 80 may be pressed together or drawn apart. The outer ends of the spindles or ends away from the buffers, project beyond the outer bearings 5, 5 and means are provided thereat for sliding the spindles whichever way it 85 is desired.

In carrying out this feature of my invention, collars 11, 11 are secured in any suitable manner adjacent the outer ends of the spindles, and the ends of the spindles are 90 recessed or provided with sockets at their centers. Slidably mounted on the base and movable parallel to the spindles are shift bars 12, 12 turning upward at their outer ends as at 13, 13 and each provided with a 95 lug 14, 14 standing upward opposite the end of the spindle. A screw 15 is threaded through each of the said lugs longitudinally of the spindle, and substantially in axial alinement therewith, the inner end of said screw being recessed and adapted to engage a ball 16 seated in the recess or socket of the end of the spindle. A stop or pin 17 projects upwardly from the shift bar 12 upon the opposite side of the collar 11 from the end of the spindle, and the screw 15 operates through the ball 16 to hold the collar in engagement with the said stop so that moving the shift bar in one direction or the other will slide the spindle in a corresponding direction. The ball 16 affords a connection between the shift bar and spindle 100 105 110

- whereby the spindle may be rotated without undue frictional resistance by pressure of the shift bar, it being understood that pressure on the glass while the same is being polished is obtained by drawing upon the shift bar. Preferably the shift bars are mounted by means of bolts 18, 18 screwed into the base and passing through slots 19, 19 in the shift bar.
- 10 Furthermore, it is preferable to operate both shift bars together and from one source, and to this end a lever 20 is pivoted to the base intermediate of its ends between the facing ends of the shift bars, and links 21, 15 22 connect the shift bars with said lever. As shown, one link 21 connects with the bottom of the lever below its fulcrum 23 and the other link 22 connects with the lever above its fulcrum and both of the links are 20 connected to their respective shift bars between the bolts 18, 18 which hold said shift bars slidably on the base.
- A weight 24 adjustably mounted on the lever 20 holds the same by gravity swung 25 as far as it will go whichever side of dead center it is placed, and it is to be understood that the parts are so arranged and adjusted that when a piece of glass is being polished that the lever is swung past dead center in one 30 direction, and when the spindles are slid to move the buffers away from each other the lever is swung past dead center in the opposite direction. In this manner, the buffers are held positively pressed toward each other 35 or positively drawn apart, and by adjusting the weight longitudinally of the lever, any desired pressure may be obtained upon the buffers for polishing the glass.
- In order to rotate the spindles, driving 40 pulleys 25, 25 are mounted on the spindles 7, 8 respectively, each between the bearings 5, 6. Preferably, these driving pulleys are rotatably mounted upon the spindles and are provided with clutch members 26, 26 adapted 45 to coöperate with clutch members 27, 28 fast upon the spindles. In the arrangement shown, the clutch members fast upon the spindles are adjacent the outer bearings and the clutch member 26, on the pulleys are on 50 the outer sides of the pulley toward the outer bearings. Springs 28, 28 are positioned upon the spindles between the inner bearings and the driving pulleys, tending to normally slide the driving pulleys outwardly 55 and engage the clutch members. Such movement of the driving pulleys is limited by means of stops 29, 29 on the base which project upwardly beneath the spindles, and these stops are so arranged and adapted 60 that the driving pulleys are prevented from moving farther before the spindles have been slid as far as they will go, as a result of which the clutch members may be thrown out by continued sliding of the spindles 65 after the pulleys engage the stops. It is to be observed, that the clutch members disengage each other as the spindles are slid to open the buffers apart, so that the buffers are automatically stopped as they are spread apart for inserting or removing glass, but 70 when a piece of glass is inserted between the buffers and they are slid toward each other the clutch members slide into engagement with each other and the buffers are rotated as they are pressed together. Obviously the 75 driving pulleys disengage the stops as the spindles are slid toward each other after the clutch members have come into engagement so there is no friction between the driving pulleys and the stops while the glass is being 80 polished.
- Around a portion of the peripheries of the buffers, preferably beneath and at the front and back of the same, is arranged a cradle 30 adapted to support the glass when it is 85 inserted between the buffers. This cradle I have shown as providing a cross-piece 31 transverse to which at its ends are arcuate side frames 32, 32 supporting between themselves a plurality of rollers 33, at sufficiently 90 close intervals to support the piece of glass which is to be polished between the buffers. The cradle is supported by means of a stud or post 34 which screws upwardly into the said cross-piece and is inserted in a suitable 95 socket in the web of the base 1. This stud or post 34 is adjustable in height, that is, may be raised or lowered within the base, and is held in such adjusted position by means of a transverse set screw 35 entering 100 the back of the base.
- Where desired, a shield 36 may be provided to surround the portion of the buffers between the ends of the cradle, and this shield I have shown as an arcuate metal 105 band provided with ears 37, 37 at one end taking around the pivot pin of the upper roller at the back of the cradle, said roller being made short enough to afford room for the said ears on the pivot pin therewith. At 110 the front of the shield, the same is provided with hooks 38 which may be snapped behind the pivot pin for the front roller, said roller likewise being made short enough to afford room so this may be done. The inner side 115 of the shield is preferably lined as at 39 with some soft material such as cork so that if the glass is thrown against the shield the glass will not become shattered and injure anybody in the vicinity.
- In the operation of my improved polishing machine, the lever 20 is swung to slide the buffers 9, 10 apart, and a piece of glass to be polished is then dropped between the buffers and rests upon the rollers 33. Then 120 for greater caution the shield 36 is closed over the top of the cradle 30, and the lever 20 is then swung to press the buffers toward each other and against the glass. As indicated by the arrows on the driving pulleys 125 130

25, these buffers are preferably rotated in opposite directions which accordingly gives the glass a tendency on one side to turn in one direction and a tendency on the other 5 side to turn in the opposite direction. In practice, it is found that the glass will turn first in one direction and then in the other and so on, which accordingly polishes the glass first on one side and then on the other 10 side. Gravity tends to normally cause the glass to drop down and engage the bottom rollers 33, but the rotation of the glass immediately draws it up between the buffers again and thus the glass oscillates somewhat 15 between the buffers and is polished all over. There is very little tendency for the glass to come out above the cradle, and a great many workmen use the machine without placing the shield over the tops of the buffers at all, 20 and obviously, the shield may be omitted entirely if so desired. When the glass is polished sufficiently the lever 20 is swung in the opposite direction which slides the buffers apart and stops their rotation. The 25 operator can then readily and without danger put his fingers between the buffers and remove the glass, at which time another piece of glass may be inserted, and so on.

Preferably the rollers 33 which support the 30 piece of glass are of suitable material at their surfaces to engage the edge of the glass without injuring the same such as rubber or the like, but I do not wish to be understood as restricting myself to any particular material.

Obviously other detail modifications and changes may be made in manufacturing my improved glass polishing machine without departing from the spirit and scope of the 40 invention, and I do not wish to be understood as restricting myself except as required by the following claims when construed in the light of the prior art.

Having thus described the invention, what 45 I claim is:

1. In a glass polishing machine, oppositely rotating buffers adapted to engage upon opposite sides of a piece of glass to be polished, and means for permitting the glass 50 to move around freely between the buffers but preventing it from coming out from between the buffers.

2. In a glass polishing machine, oppositely rotating buffers adapted to engage 55 upon opposite sides of a piece of glass to be polished, means for permitting the glass to move around freely between the buffers but preventing it from coming out from between the buffers, and means for moving 60 the buffers apart for inserting or removing the glass.

3. In a glass polishing machine, oppositely rotating buffers adapted to engage upon opposite sides of a piece of glass to be 65 polished, means for permitting the glass to

move around between the buffers but preventing it from coming out from between the buffers, and means for both stopping rotation of the buffers and moving said buffers apart while being stopped for inserting or removing the glass. 70

4. In a glass polishing machine, buffers arranged to rotate in vertical and parallel planes, driving means for rotating said buffers in opposite directions, clutch means 75 for connecting said buffers and driving means, and means for moving said buffers toward and away from each other as said clutch means are thrown in and out whereby the buffers may be moved apart and stopped 80 for removing a piece of glass from between them.

5. In a glass polishing machine, buffers arranged to rotate in vertical and parallel planes, driving means for rotating said 85 buffers in opposite directions, clutch means for connecting said buffers and driving means, means for moving said buffers toward and away from each other, and means for separating said clutch means for stopping rotation of the buffers as the buffers 90 are moved away from each other.

6. In a glass polishing machine, buffers arranged to rotate in vertical and parallel planes, means for rotating said buffers in 95 opposite directions, and a cradle for supporting a piece of glass between said buffers and preventing its removal except upwardly against gravity whereby rotation of the buffers will polish the glass. 100

7. In a glass polishing machine, buffers arranged to rotate in vertical and parallel planes, means for rotating said buffers in opposite directions, and a cradle having a plurality of rollers for engagement with the 105 edge of a piece of glass between said buffers whereby the glass is prevented from coming out from between the buffers as the buffers rotate and polish the glass.

8. In a glass polishing machine, buffers arranged to rotate in vertical and parallel planes, means for rotating said buffers in opposite directions, a cradle passing beneath the buffers for supporting and holding a piece of glass therebetween, and a shield 115 adapted to pass over the buffers and connect with the ends of the cradle whereby the glass cannot be thrown out from between the buffers in any direction as the buffers rotate. 120

9. The combination with a bed or base, a pair of rotatable spindles, shift bars slideable on said base and having portions opposite the ends of the spindles, balls between the ends of the spindles and said portions, 125 whereby sliding said shift bars in one direction will obtain a pressure on the ends of said spindles with minimum friction to slide the spindles, and means for sliding the spindles in the other direction. 130

10. The combination with a bed or base, a pair of rotatable spindles, shift bars slideable on said base and having portions opposite the ends of the spindles, balls between 5 the ends of the spindles and said portions, whereby sliding said shift bars in one direction will obtain a pressure on the ends of said spindles with minimum friction to slide the spindles, means for sliding the spindles 10 in the other direction, and means for sliding said shift bars at the same time.

11. The combination with a bed or base,

a pair of rotatable spindles, shift bars slideable on said base and having means for sliding the spindles at the same time and in 15 the direction of sliding of the slide bars, a lever pivoted to swing across dead center whereby it will rest in whichever end of its swing to which it is swung, and means connecting said shift bars and lever whereby 20 the spindles are shifted at the same time and held by the lever.

CHARLES F. LINDEBURG.
